Geo. P. Kimmel
ATTORNEY.

UNITED STATES PATENT OFFICE

CHARLES J. SCHMITT, OF ALGOMA, WISCONSIN

TABLE

Application filed December 10, 1930. Serial No. 501,415.

This invention relates to tables and has for its object to provide, in a manner as herein-after set forth, a table having means so constructed and arranged to provide for the firm seating of the table upon an uneven floor.

A further object of the invention is to provide, in a manner as herein-after set forth, a table having means so constructed and arranged to prevent the rocking thereof upon an uneven floor.

A further object of the invention is to provide, in a manner as herein-after set forth, a table having means coacting with one of the legs thereof to prevent the rocking of the table upon an uneven surface.

A further object of the invention is to provide, in a manner as herein-after set forth, a table having one of its legs capable of being adjusted relative to the table top to overcome the rocking of the table upon an uneven surface.

A further object of the invention is to provide, in a manner as herein-after set forth, a table including an adjuster to prevent the table from rocking upon an uneven floor.

A further object of the invention is to provide, in a manner as herein-after set forth, a table including a plurality of fixed legs, an adjustable slotted leg capable when adjusted to overcome the rocking of the table upon an uneven surface, and means coacting with the slotted leg for maintaining the latter in its adjusted position.

A further object of the invention is to provide, in a manner as herein-after set forth, a table including an adjustable slotted leg of a different length from that of the other legs of the table and providing when adjusted and held in its adjusted position the preventing of the table rocking upon an uneven floor.

Further objects of the invention are to provide, in a manner as herein-after set forth, a table for the purpose referred to which is simple in its construction and arrangement, strong, durable, compact, expeditiously arranged to prevent rocking thereof upon an uneven surface, thoroughly efficient in its use, readily assembled and comparatively inexpensive to manufacture.

With the foregoing and other objects in

view, the invention consists of the novel construction, combination and arrangement of parts as herein-after more specifically described, and illustrated in the accompanying drawings, wherein is shown an embodiment 55 of the invention, but it is to be understood that changes, variations and modifications can be resorted to which fall within the scope of the claims hereunto appended.

In the drawings wherein like reference 60 characters denote corresponding parts throughout the several views:—

Figure 1 is a perspective view broken away of a table in accordance with this invention.

Figure 2 is a section on line 2—2 Figure 1. 65

Figure 3 is a section on line 3—3 Figure 1.

Figure 4 is a perspective view of the anchoring member for the clamping element for the wedging block.

Figure 5 is a perspective view of the wedging block for the adjustable leg.

The body portion of the table is in the form of a frame including four rectangular side members 1, 2, 3 and 4 each standing on its lower longitudinal edge. The ends of the 75 member 1 are spaced from one end of the members 2, 3 and the ends of the member 4 are spaced from the other ends of the members 2, 3. The members 1 and 4 are connected to the members 2, 3 and for such purpose coupling pieces are provided which have their ends dovetailed in the inner faces of the side members. The coupling pieces are disposed at an inclination relative to and of the same height as the side members. One 85 of the coupling pieces is indicated at 5 and the others at 6. The coupling piece 6 between the side members 1 and 3 is not shown. The coupling piece 5 connects side member 3 with side member 4. The coupling pieces 90 are also secured in any suitable manner to the side members. The dovetailed connection between a coupling piece and a pair of side members is indicated at 7, Figure 3.

The coupling piece 5 centrally thereof is 95 provided with an opening 8'. The table includes three stationary legs 8, 9 and 10 and an adjustable leg 11 of less length than the other legs. The leg 11 in proximity to its top is formed with a slot 12 100

The table includes three stationary legs 8, 9 and 10 and an adjustable leg 11 of less length than the other legs. The leg 11 in proximity to its top is formed with a slot 12 100

extending lengthwise thereof. The upper portion of leg 8 is positioned between one end of side member 1 and one end of side member 3. The upper portion of leg 9 is positioned between the other end of side member 1 and one end of side member 2. The leg 10 is positioned between the other end of side member 2 and one end of side member 4. The upper portion of leg 11 is positioned between the other end of side member 3 and the other end of side member 4. The legs 8, 9 and 10 abut against the lower face of the table top 13 and are fixedly secured in position by holdfast devices 14 which extend through the coupling pieces 6 and engage in the legs. The table top 13 is suitably secured upon the body portion of the table by any suitable means.

Extending into the opening 8' and abutting against the inner face of the coupling piece 5 is an anchoring member for the clamping element for wedging block. The said element and block will be hereinafter referred to. The anchoring member comprises a tubular body portion 13' which is interiorly threaded throughout and has its rear end provided with an apertured annular flange 14' seating against the rear face of and secured to the coupling piece 5 by holdfast devices 15 extending through the aperture in the flange. The tubular body portion has its forward end flush with the forward face of the coupling piece 5.

The clamping element is rotatable and it comprises a stem 16 having its inner portion thereof threaded as at 17 for engagement with the threads of the anchoring member. The outer end of stem 16 terminates in a flared head 18 of materially greater diameter than the stem 16. The outer end of the head 18 is formed with radially disposed spaced lugs 19 to facilitate the gripping thereof when rotating the clamping element.

The wedging block or member comprises a rectangular body 20 standing upon one end and having its rear face oppositely beveled as at 21, 22. The block centrally thereof is formed with an opening 23 for the passage of the stem 16. The block when positioned on the stem 16 is arranged against the inner end of the head 18. The bevels 21, 22 extend lengthwise of the inner face or rear face of the body 20.

The upper portion of leg 11 is positioned between the other ends of the sides 3, 4 and adjustable relative to such ends. The stem 16 of the coupling element extends through the slot 12. The head 18 of the clamping element is arranged exteriorly of the leg 11 and the wedge block is interposed between the head 18 and leg 11 and straddles the latter. The clamping element maintains the wedge block in wedging engagement with the leg 11, under such conditions maintain-

ing the leg 11 stationary. When the clamping element is shifted outwardly to release the wedge block the leg 11 can be adjusted to the desired position and when so adjusted the clamping element is shifted inwardly to provide for the wedge block wedging the leg 11 in stationary position.

If the table is mounted on an uneven surface whereby the table will rock, such action or objection can be overcome by loosening the leg 11 and the latter will either raise or drop, whichever the case may be and after leg 11 is retightened the rocking will be eliminated.

It is thought that the many advantages of a table constructed in a manner as herein referred to and for the purpose described can be readily understood and although the preferred embodiment of the invention is as illustrated and described, yet it is to be understood that changes in the details of construction can be had which fall within the scope of the invention as claimed.

What I claim is:—

1. In a means to prevent the rocking of a table upon an uneven surface, the combination with one of the legs of the table, said leg being shorter than the other legs of the table, provided with a slot disposed lengthwise thereof and capable of being raised or lowered to compensate for the uneven surface to overcome rocking of the table, of an interiorly threaded tubular anchoring member secured to the table, an adjustable, rotatable coupling element threadedly engaging with said member, extending through said slot and having a head at its outer end, and a wedge block shifted by said head and acting on said leg for wedging the latter stationary in its shifted position when said element is adjusted inwardly.

2. In a means to prevent the rocking of a table upon an uneven surface, the combination with one of the legs of the table, said leg being shorter than the other legs of the table, provided with a slot disposed lengthwise thereof and capable of being raised or lowered to compensate for the uneven surface to overcome rocking of the table, of an interiorly threaded tubular anchoring member secured to the table, an adjustable, rotatable coupling element threadedly engaging with said member, extending through said slot and having a head at its outer end, a wedge block shifted by said head and acting on said leg for wedging the latter stationary in its shifted position when said element is adjusted inwardly, and said block being oppositely beveled for overlapping said leg.

In testimony whereof, I affix my signature hereto.

CHARLES J. SCHMITT.
